UNITED STATES PATENT OFFICE.

JAMES G. MASTIN, OF CHICAGO, ILLINOIS, ASSIGNOR, BY MESNE ASSIGNMENTS, TO
JAMES G. KELLOGG, OF CHICAGO, ILLINOIS.

ATOMIZER.

1,141,721.

Specification of Letters Patent.

Patented June 1, 1915.

Application filed April 19, 1912. Serial No. 691,940.

To all whom it may concern:

Be it known that I, JAMES G. MASTIN, a citizen of the United States of America, and resident of Chicago, Cook county, Illinois, have invented a certain new and useful Improvement in Atomizers, of which the following is a specification.

My invention relates to atomizers in general.

10 The object of my invention is to provide a novel form of atomizer having provision for cutting off the air and thus discharging a stream of liquid alone.

For this purpose my invention contemplates broadly an atomizer having a movable valve member in which the atomizing action takes place and by means of which the air can be cut off and the liquid alone discharged from the outlet of the atomizer.

20 To this and other useful ends my invention consists in matters hereinafter set forth and claimed.

In the accompanying drawings, Figure 1 is a vertical section of the upper portion of 25 an atomizer embodying the principles of my invention. Fig. 2 is a perspective of the movable valve member. Fig. 3 is a longitudinal sectional view showing another form of my invention.

30 As thus illustrated, my invention comprises a rotary valve member or plug A mounted to turn in a head or casing B. The said valve member A has a T-shaped passage extending transversely therethrough to provide the three lateral and interconnected openings a , a' and a'' . These openings, it will be seen, are disposed ninety degrees apart circumferentially of said member.

35 The casing B has three passages b , b' and b'' , located in such manner that they register respectively with the openings a , a' and a'' , when the said member is in atomizing position. With the construction shown in Fig.

40 1, the head or casing B is fixed on the top of a can or tank C provided with an inlet c for compressed air. A tube c' leads downward from the passage b' to the bottom of the can or tank, to receive the liquid, and the passage b'' receives the compressed air.

45 50 A nozzle D, of any suitable character, is disposed in position to discharge the liquid and air escaping from the valve member through the passage b' of the casing. Thus the atomizing action takes place in the valve member A, when the air and liquid come to-

gether therein. The member A can, it will be seen, be turned to cause the openings a' and a'' to register respectively with the passages b and b' , and in such case the air is cut off and only the liquid escapes. Also, it 60 will be seen that the valve can be turned to a position to cut off the passage b , and thus close the outlet of the atomizer. In fact, the construction is such that the member A can be turned to cut off anyone of the three 65 passages b , b' and b'' and connect together the other two thereof. Thus, air alone, if desired, can be discharged from the can or tank.

In Fig. 3 the invention is shown modified 70 to serve as a hose nozzle. The head E has passages e , e' and e'' , which correspond respectively to the passages b , b' and b'' of the previous construction. The passages e' and e'' are connected respectively to the liquid 75 and air pipes F and G, and the passage e is made flaring to permit a direct and spray-like discharge from the valve member H, which is identical with the member A of said other construction. With this construction either air, or liquid, or both, can be discharged from the end of the nozzle.

In either form of my invention the rotary three way valve controls the entire situation and provides a passage in which the 85 primary atomizing action takes place. Thus the device can be governed at will to throw either a cloud of spray or a stream of liquid alone. And, moreover, the same valve can be used for entirely closing the outlet of 90 the device.

As indicated in Fig. 1, the pipe c may lead to the bottom of the can or tank C, and in this way the air will bubble up or rise through the body of the liquid. Such action 95 will saturate the air with the liquid, if the latter be of a sufficiently volatile nature, and by shutting off the passage b' , only this mixture of air and vapor will be discharged.

What I claim as my invention is:

1. An atomizer comprising a movable valve member and casing therefor, having air and liquid passages which come together within said member, the casing having a discharge opening leading from the side of said 105 member, opened and closed by movement of said member.

2. An atomizer comprising a movable valve member and casing therefor, having passages whereby the atomizing action or 110

2

point where the air and liquid come together is within said member, said member having three lateral openings which inter-communicate internally of said member, and said 5 casing having three passages each of which registers with one of said openings when the said member is in atomizing position, said member cutting off one of said passages and leaving the others open when adjusted and leaving the others open when adjusted 10 to a different position.

3. An atomizer comprising a rotary valve member and casing therefor, having passages whereby the atomizing action or point where the air and liquid come together is within said member, means for supplying compressed air to one of said passages, and means for supplying liquid to the second 15 passage, the third passage serving to discharge the air and liquid intermingled with 20 in said member, and rotation of said member directly controlling all of said passages.

4. An atomizer comprising a movable valve member and casing therefor, having passages whereby the atomizing action or 25 point where the air and liquid come together is within said member, said member being rotatable, and the arrangement of said passages being such that operation of said member serves to cut off one of said passages and 30 leave the other open, to change the character of the discharge.

5. An atomizer comprising a movable valve member and casing therefor, having three passages whereby the atomizing action 35 or point where the air and liquid come together is within said member, said member being rotatable, and the arrangement of said passages being such that operation of said member serves to cut off any one of said 40 passages and connect together the other two passages, to permit discharge of either the air or liquid alone.

6. An atomizer comprising a rotatable valve member and casing therefor having 45 passages whereby the atomizing action or point where the air and liquid come together is within said member, said openings being disposed ninety degrees apart and in line with each other circumferentially of said 50 member.

7. An atomizer comprising a movable valve member and casing therefor, having 55 passages whereby the atomizing action or point where the air and liquid come together is within said member, said member being rotatable, and the arrangement of said passages being such that operation of said member serves to cut off the air and permit the liquid to escape alone.

8. An atomizer comprising a movable 60 valve member and casing therefor, having passages whereby the atomizing action or point where the air and liquid come together is within said member, said member being rotatable, and the arrangement of said 65 passages being such that operation of said member serves to cut off the liquid and permit the air to escape alone.

9. An atomizer comprising a movable valve member and casing therefor having 70 air and liquid outlet passages whereby the atomizing action or point where the air and liquid come together is within said member, said member being rotatable, and the arrangement of said 75 passages being such that operation of said member serves to cut off the liquid and permit the air to escape alone, and means for introducing compressed air below the surface of the liquid, the air outlet passage being entirely above the surface 80 of the liquid, whereby the escape of the air alone may carry with it any vapor from said liquid.

10. An atomizer comprising a movable valve member and casing therefor having 85 passages whereby the atomizing action or point where the air and liquid come together is within said member, and whereby the same are discharged from the side of said member, the outlet end of the atomizing 90 passage through said member being disposed in position to be cut off by rotation thereof.

11. An atomizer comprising a movable valve member and casing therefor, having 95 air and liquid passages which come together within said member, said casing having a discharge passage in a fixed portion thereof, said discharge passage being disposed in position to be opened and closed by movement 100 of said member.

12. An atomizer comprising a movable valve member and casing therefor, having 105 passages whereby the atomizing action or point where the air and liquid come together is within said member, and whereby the same are discharged from the side of said member, said member having a handle, and the arrangement of said passages being such that adjustment of said member serves to 110 cut off the air and permit liquid alone to escape.

Signed by me at Chicago, Illinois, this eighth day of April, 1912.

JAMES G. MASTIN.
